FRICITION HINGE

Walter J. Sorrow, Jr., New Britain, Conn., assignor
to The Stanley Works, New Britain, Conn., a
corporation of Connecticut

Application January 29, 1931, Serial No. 511,984

6 Claims. (Cl. 4—236)

This invention relates to hinges provided with frictional means for preventing the pivoted members from swinging freely. As an instance of a use to which the present invention may be applied, reference may be had to a toilet seat, as my improved arrangement is peculiarly adaptable to such use.

The aim of the present invention is to provide an improved hinge having various features of novelty and advantage and which is particularly characterized by the fact that it will prevent the seat and the cover from slamming to closed positions, thus avoiding the annoyance and embarrassment which would otherwise result from the noise incident to such closing. The construction of my improved hinge is such that the seat and cover cannot be easily and deliberately opened and closed with such rapid movement as to cause jars and noise when they are brought to their extreme positions, and the members, after they are started on their downward movements and then released, will slowly continue their downward movements and come to rest with substantially no noise. My improved hinge is further such that, while slamming of the members and the resultant noise and embarrassment are avoided, the seat and cover may be raised and lowered with little effort and, in fact, with an effort only slightly greater than that which would be required if these members were free swinging.

A further aim of the invention is to provide a hinge of this sort which is simple in construction, which is provided with means of a practical, durable and effective nature for exerting frictional forces on the seat and cover, which is effective in operation, and which may be easily assembled and adjusted.

Other objects will be in part obvious, and in part pointed out more in detail hereinafter. The invention accordingly consists in the features of construction, combination of elements, and arrangement of parts which will be exemplified in the construction hereinafter set forth and the scope of the application of which will be indicated in the appended claims.

In the accompanying drawings, wherein is shown, for illustrative purposes, one of the many embodiments which the present invention may take,

Fig. 1 is a top plan view of my improved hinge applied to the seat and cover of a toilet;

Fig. 2 is an elevational view looking at the rear end of the assembly shown in Fig. 1;

Fig. 3 is a side elevational view of the assembly;

Fig. 4 is a side elevational view of one of the

posts in which a frictional element is mounted; and

Fig. 5 is a transverse sectional view taken substantially on line 5—5 of Fig. 3.

Referring to the drawings in detail, A denotes the cover and B the seat of a toilet. These members may be of any suitable construction and made of any desired material. At their rear ends, they have rectangular extensions A' and B', respectively, each provided with flat side faces.

The numeral 10 designates posts adapted to be suitably secured to the toilet bowl. For example, each of these posts may have a threaded stem 11 adapted to extend through a vertical opening at the rear end of the bowl (not shown) and clamped in position by suitable nuts (not shown). These posts have collars or shoulders 12 adapted to rest upon the top surface of the bowl. Each post has a ring-like head 13, the periphery of the opening of which may be roughened; for example, it may be provided with transverse teeth or corrugations 14. Located in the opening in each head, and held against rotation therein by the teeth 14, is a slightly compressible friction member 15 which is preferably made of wood impregnated with a lubricating material, such as oil. Each friction member, in the form of an apertured washer or disk, is slightly thicker than the head 13 so that the friction member extends slightly to each side of this head, as shown most clearly in Fig. 5.

The extension B' of the seat is positioned between the heads, and it has at each side a bearing member 20, which is here shown as being in the form of a round washer, preferably formed of brass. These washers may be considered as constituting hinge leaves. They are connected to the seat so as to turn therewith, and to this end each washer may have riveted to it two studs 21 which engage in recesses 22 in the seat. The outer faces of these washers or hinge leaves bear against the opposed surfaces of the friction elements 15. The seat has a through opening in which may be fitted a tube 23 which, in length, is substantially equal to the width of the projection B'. If desired, this tube may be omitted.

The numeral 24 designates a pin extending through and fitting in the central openings of the friction members 15 so as to be supported thereby. The opposite ends of this pin or spindle are threaded so as to receive nuts 25. The washers or hinge leaves 20 have central openings through which the pin 24 extends so that these washers, together with the toilet seat, are journalled on and may swing about the pin as an axis. Carried by the cover at each side of the ex-

tension A' is a hinge leaf 30. These hinge leaves may be secured to the cover in any suitable manner, as by means of studs 31 similar to the studs 21. The hinge leaves 30 depend from the cover, 5 and each engages against the outer face of a respective friction member 15. The leaves 30 have openings 32 which closely surround the pin 24 so that the leaves have a bearing on and may swing about this pin.

10 The manner in which the parts are assembled is shown most clearly in Fig. 5. After the parts have been assembled, the frictional engagement between each frictional member 15 and the respective hinge leaves 20 and 30 may be nicely 15 and quickly adjusted by merely turning the nuts 25 relative to the pin 24.

15 It will be observed that the parts are tied together by the pin 24 and the nuts 25, and the frictional engagements between the friction elements and the hinge leaves are all simultaneously adjusted, thus facilitating the setting up of the device and imparting simplicity thereto. The seat and the hinge have independent movements so that one may be raised or lowered without 20 affecting the position of the other. The parts are so adjusted that each, the cover and the seat, is retarded in its swinging movement by the frictional elements, and the friction between the leaves and the friction elements is such as to 25 permit of the seat and hinge to be swung open and closed without the expenditure of much effort. When either the seat or the cover is swung forwardly from its open position slightly past dead center and then released, it will continue 30 to swing downwardly with a slow, steady, easy movement so that it will come lightly to rest without any annoying jars or bangs. It may further be stated that the frictional elements are made of such material as to require no subsequent lubrication; frequent adjustments are not necessary; and wear on these elements over 35 long periods of time is practically negligible; in short, they have a long, useful life.

40 As many changes could be made in the above construction and many apparently widely different embodiments of this invention could be made without departing from the scope thereof, it is intended that all matter contained in the above description or shown in the accompanying drawings shall be interpreted as illustrative and not in 45 a limiting sense.

45 It is also to be understood that the language used in the following claims is intended to cover all of the generic and specific features of the invention herein described and all statements of the scope of the invention which, as a matter of language, might be said to fall therebetween.

What is claimed is:

50 1. In combination, a pair of fixed frictional elements each having a pair of parallel surfaces, one at each end, a single pin extending through said frictional elements, a pair of hinge leaves adapted to be connected to a first swinging member and respectively engaging the opposed faces 55 of said frictional elements, a pair of hinge leaves adapted to be connected to a second swinging member and respectively engaging the extreme surfaces of said frictional elements, and means associated with said pin for adjusting the friction between said leaves and elements.

55 2. In combination, a pair of posts each having a ringlike head and each head having an opening

the wall of which is serrated, a solid, slightly compressible friction washer located in each head and held against movement relative thereto by said serrations, a swinging member having a portion located between said posts and provided with surfaces respectively engaging the opposed faces of said friction washers, a second swinging member, a pair of hinge leaves secured thereto and respectively engaging the extreme faces of said friction washers, a pin extending through said hinge leaves and said portion of said first swinging member and through openings in said friction washer, and nuts on said pin adapted to engage against the outer faces of said hinge leaves.

60 3. In combination, a pair of posts, a compressible washer fixedly carried by each post, said washers being provided with aligned apertures, a swinging member having an opening, a tube in said opening, hinge leaves secured to said swinging member and respectively engaging the opposed faces of said compressible washers, a second swinging member, a pair of hinge leaves secured thereto and respectively engaging the extreme faces of said washers, a pin extending through said leaves, tube, and washers, and nuts 65 on said pin.

65 4. A friction hinge for a toilet seat and cover, comprising a pair of hinge leaves adapted to be secured to the seat at opposite sides thereof, a second pair of hinge leaves adapted to be secured to the cover at the opposite sides thereof, the seat and cover hinge leaves being disposed in registering and spaced apart relation at opposite sides of the seat and cover, stationary supports projecting between the registering hinge leaves, 70 a friction device carried by each stationary support, and a common adjusting means for simultaneously and equally binding the registering hinge leaves against the opposite sides of their respective friction devices to equalize the tension 75 on the hinge leaves at opposite sides of the seat and cover.

75 5. In a friction hinge, the combination of spaced apart pairs of hinge leaves adapted for attachment to separate elements to be hinged and 80 with the adjacent leaves of each pair disposed in spaced apart relation and with all of the hinge leaves in axial register, a stationary friction device disposed in line with the hinge leaves and between the respective leaves of each pair, abutment means disposed between the inner adjacent hinge leaves, and compression means operable against the outer hinge leaves for compressing the same against the friction devices to equalize the pressure upon both friction devices and 85 equalize the resistance to movement of the hinge leaves of each pair.

85 6. In combination, a pair of posts, a friction washer fixedly carried by each post, a swinging member having a portion located between said posts and provided with surfaces respectively engaging the opposed faces of said friction washers, a second swinging member, a pair of hinge leaves secured to the latter and respectively engaging the extreme faces of said fixed friction washers, 90 a single pin extending through said hinge leaves and said portion of said first mentioned member and through openings in said friction washers, said pin being supported by said washers, and means on the pin for adjusting the friction between 95 said leaves and friction washers.

WALTER J. SORROW, JR.
